WILLIAM LAYMAN, OF WEST FORT WILLIAM, ONTARIO, CANADA, ASSIGNOR OF ONE-FIFTH TO FRANK FALK AND TWO-FIFTHS TO AUGUST BERGER, BOTH OF WEST FORT WILLIAM, ONTARIO, CANADA.

GRAIN-CAR DOOR AND LOCKING MECHANISM THEREFOR.

1,262,064.

Specification of Letters Patent.

Patented Apr. 9, 1918.

Application filed March 18, 1916. Serial No. 85,170.

To all whom it may concern:

Be it known that I, WILLIAM LAYMAN, a subject of the King of England, residing at West Fort William, in the Province of Ontario and Dominion of Canada, have invented certain new and useful Improvements in Grain-Car Doors and Locking Mechanism Therefor, of which the following is a specification.

10 This invention has relation to certain new and useful improvements in grain car doors, and has for its primary object, the provision of a sectional door and a duplex locking mechanism therefor.

15 A further object of the invention resides in the provision of an improved locking mechanism which may be operated only by a special form of key.

With the above and other objects in view, 20 the invention resides in the novel construction, combination, and arrangement of parts as hereinafter set forth in the specification, pointed out in the claims and shown in the drawings; in which—

25 Figure 1 is a view in front elevation of a car door constructed in accordance with my invention and locked in a closed position;

Fig. 2 is a vertical section on the plane of line 2—2 of Fig. 1, looking in the direction indicated by the arrows;

30 Fig. 3 is an enlarged elevation of the locking mechanism;

Fig. 4 is a vertical section on the line 4—4 of Fig. 3, looking in the direction indicated by the arrows;

35 Fig. 5 is an elevation of the lock case with the cover removed to show the operative parts of the lock in normal position;

Fig. 6 is a vertical transverse section 40 through the lock case and the parts positioned in the same;

Fig. 7 is a sectional view on the plane of line 7—7 of Fig. 6, looking in the direction indicated by the arrow;

45 Fig. 8 is a perspective view of the lock case cover removed;

Fig. 9 is a detail perspective view of the slotted lever supporting plate;

Fig. 10 is a detail perspective view of one of the levers;

Fig. 11 is a detail perspective view of the lever supporting plate;

Fig. 12 is a detail perspective of one of the door section engaging members and the parts supporting the same; and

Fig. 13 is a detail view of one of the receiving cups carried by the door section.

Referring now more particularly to the drawings, wherein similar reference characters designate corresponding parts throughout the several views, 1 and 1^a designate the channel bars at the opposite sides of a doorway of a grain car or the like, while 2 and 3 designate, respectively, the lower and upper door frame members.

A lower door section 4 is mounted to travel horizontally on the sill or lower door frame member, while an upper door section 11 is mounted on the lower door section, as at 4', in Figs. 1 and 2, and is adapted to travel horizontally thereon. When the door sections are moved horizontally, they pass in rear of the channel bar 1; that is, they pass through an opening provided between the channel bar 1 and the body of the car.

The lower door section 4 and the upper door section 11 are provided, respectively, with cup brackets or keepers 19 and 20 which are adapted to receive the free ends, respectively, of the pivoted door engaging members 21 and 22 to lock the door sections 4 and 11 in a closed position. The door engaging member 21 is carried at one end of a shaft 23, which has its central portion mounted in a suitable bearing 24 secured upon the inner edge of the channel bar 1.

At one end, shaft 23 is provided with a crank 23' that has connected thereto one end of a connecting rod or operating member 25, the opposite end of which said rod is bifurcated, as at 26, and pivoted upon the operating lever 27. Upon reference to Fig. 12, it will be seen that upon movement of shaft 23, the locking member 21 will be moved in the arc of a circle whereby, upon entrance 95 into the cup bracket 20, the respective door section will be locked in a closed position.

Door engaging member 22 is carried by one end of a shaft 28, which is mounted in a corresponding bearing 29 carried upon the 100

inner edge of the channel bar 1, and the inner end of the shaft 28 has a crank 28' formed therefrom and connected with one end of a connecting rod 30, as shown. The 5 opposite end of connecting rod 30 is pivoted to the laterally turned end of a connecting link or operating member 31, which latter is pivoted to the pin 32, projecting from one side of an operating lever 33. Levers 27 10 and 33 are pivotally mounted upon a shaft 34 having bearing through the ears 35 of the lever supporting plate 36, which latter is secured upon the outer face of the channel bar 1 and between the outwardly directed 15 longitudinal edges of the same. It will be understood that the levers 27 and 33 are positioned between the ears 35, and that the said levers 27 and 33 have enlarged and pointed ends or heads 37, preferably of rectangular form in cross section and provided with peripheral grooves 38 inwardly of the pointed ends of the heads 37.

The grooves 38 are provided to permit the heads of said levers 27 and 33 to be engaged in the recesses or notches 39 formed in the upstanding edge 40 of the plate 41, which latter is secured transversely upon the support 42 mounted on the main portion of the channel bar 1. The upstanding edge 30 40 of the plate 41 is provided with a central tongue 43 separating the recesses and also separating the arms 44. These arms 44 are extended at right angles to the portion 40 and support the hinged plate 45, which will be later described. One corner of plate 41 is also cut away as at 41' in order to permit operation of rod 30 (see Figs. 3 and 9). The arms 44 also rest upon the cover 46 of the lock case 47 which latter has sliding movement longitudinally between the arms 44 and the support 42, and the pointed ends of the head 37 of the levers 27 and 33 will serve to limit downward movement of the lock case 47. The cover 46 has outwardly directed side 45 flanges 48 through which any appropriate securing members may be extended to fasten said cover 46 upon the lock case 47, the securing members passing through the sides of the lock case 47. When the lock case 47 is in its lowermost position, the main offset portion of the U-shaped member 49, mounted upon the outer face of the cover 46, extends through the opening 50 in the hinged plate 45, previously mentioned, and bears against the outer face of the latter to lock the same against the arms 44 and thereby prevent levers 33 and 27 from being withdrawn from the plate 41. The hinged plate 45 is connected by a suitable hinge 51 to the depending edge 52 of plate 53, which latter has its opposite edge directed upwardly and secured as shown at 54 to the channel bar 51. The plate 53 is provided with a suitable opening 55 through which extends the spring 56 having one end connected with the upper end

of the lock case 47, while its other end is secured in a bracket arm 57, secured to the main portion of the channel bar 1, above the plate 53. Plate 53 may also be cut away at a point in alignment with the cut away portion 41' or plate 41, so as to permit free operation of connecting link 30, as is obvious. 70

The lock case 47 is locked in its lowermost position with the spring 56 under tension, by means of the outwardly directed bolts 58 75 which project through the sides of the lock case 47 and extend into openings provided for the same in the sides of channel bar 1, suitable openings being provided for bolts 58, in the outer edge of the side of the lock case 47 and the opposite edges of the cover 46, as will be readily recognized upon referring to Figs. 3, 7, 8 and 10 of the drawings. The bolts 58 have their inner ends loosely mounted upon the upper diverging 80 ends of the bar or bolt carrying members 59 which are pivoted, intermediate their opposite ends, upon the parallel post 60 projecting from the back of the lock case 47. The diverging bolt carrying members 59 are resiliently retained in the normal or locking position, by means of the springs 61 which have their central portion coiled about an upper post 62, while their legs may be suitably secured to member 59, or at any other point. The bolt carrying members 59 are positioned outwardly of the outer ward or 90 ward plate 64^a which is also mounted upon the supporting posts 60 and upon a lower supporting post 63. An inner ward or plate 64 is also mounted upon the posts 60 and 63 and spaced from the back of the lock case 47. The inner plate 64 is also spaced from the intermediate spacing plate 64^b and between the plates 64^a and 64 are positioned the substantially parallel pivoted lock members 65 which are pivoted upon the posts 60 and have their upper ends directed outwardly toward the opposed sides of the lock case 47, a second spring 66 being provided to press 100 against the lock members 65 and which serves to retain the inwardly directed lower ends 67 of the members 65 in engagement with the opposite sides of the spacing block 68 in the lower end of the lock case 47. The spacing block 68 is secured to the back of the lock case 47 and the cover 46 in a suitable manner, as shown at 69 in Fig. 6, and the extended end 70 of the spacing plate 64 is suitably secured to the spacing block 68. 110 The lower ends 67 of the pivoted lock members 65 are provided with beveled shoulders 71 which are normally engaged with the rounded lower end 72 of the bolt carrying members 59 to prevent operation of the latter 120 without the use of the proper key 73, which is provided with opposite wings 74, for separating the lower ends of the lock members 65, while the parallel wings 75 of key 73 separate the lower ends 72 of the bolt carry- 125 130

ing members 59. It will also be seen that the proper form of key, such as shown at 73, is provided with recesses 76 and end wings 77 in order that the key may be rotated over suitable ribs or wards of ordinary construction (not shown).

From the foregoing, it will be readily seen that when the parts of the locking mechanism are in the position shown in Figs. 1, 3, 4, 5 and 6, the lower door section 4 and the upper door section 11 will be securely locked in a closed position. However, upon insertion of the proper key 73, in the lock case 47, and turning the key, the bolts 58 will be drawn inwardly of the lock case 47, permitting the springs to act so as to draw upward the case 47 and thereby release the hinged plate 45 from engagement with the loop or detent 49 and permit the levers 27 and 33 to be engaged by the operator and swung out, so as to cause the operating members 25 and 31 to withdraw the door engaging members 21 and 22 out of engagement with the respective keepers 19 and 20.

The door sections 4 and 11 may then be moved horizontally, either simultaneously or selectively to an open position. When the door sections are again closed, they may be readily locked, by placing the levers 27 and 33 in position in the notches 39 of plate 41, thereby forcing the door engaging members 21 and 22 into the cup brackets or keepers 19 and 20, bringing the hinged plate 45 to position upon the arms 44 and drawing downwardly the lock case 47, while the bolts 58 will be automatically moved into the opening provided therefor in the sides of the channel bar 1.

While I do not wish to limit myself in any way, it is pointed out that the several securing members shown in Figs. 1 and 4 may have their heads countersunk in respective plates or strips while the nuts or fastening members may be likewise positioned with respect to the door sections, thereby providing comparatively smooth surfaces which will permit of operation of the door members with greater ease.

While the preferred embodiments of the invention have been shown and described, it will be understood that minor changes in the details of construction, and arrangement of parts may be resorted to within the scope of the appended claims without departing from the spirit of the invention or sacrificing any of the advantages of the same.

What is claimed is:—

1. A car door, a pair of shafts, door engaging members carried by said shafts to lock said door in closed position, operating levers one for each of said shafts, connections between said shafts and their respective operating levers, and means common to said levers for locking said levers in one position.

2. A car door, a pair of shafts, means carried by said shafts and said door for locking the latter in one position, a pair of levers, connections between said levers and the respective shafts, said levers having enlarged free ends, means engaged with said enlarged free ends to support said levers in one position, means for locking said levers with said last-mentioned means, and means for normally holding the last-mentioned locking means in operative position.

3. A car door movable horizontally for opening and closing, a vertically extending channel bar to one side of said car door, means mounted upon said channel bar for locking said door in one position, levers for operating said means, and means within the channel of said channel bar for locking said levers in one position.

4. A car door movable horizontally for opening and closing, a vertically extending channel bar to one side of said car door, door engaging members mounted upon said channel bar to lock said door in one position, means within the channel of said channel bar for operating the said door engaging members, and means within the channel of said channel bar for retaining the operating means in normal position.

5. The combination with a door; of door engaging members, means for effective operation of said door engaging members, a lock case movable to an operative position to lock said means in its inoperative position, means carried by said movable lock case for retaining the latter in its operative position, and means for moving the lock case to its inoperative position when released from its retaining means.

6. The combination with a door; of door engaging members, levers for controlling movement of said door engaging members, means for holding said levers in one position, a lock case movable to a position in which it is operable to render said means effective, bolts projecting through said lock case to retain the latter in one position, and means for effective operation of said bolts.

7. The combination with door engaging members; of a movable case, a guide-way for said movable case, bolts projecting through said case and normally extending in the opposite portions of said guide-way to retain said case in one position, means within said case for supporting said bolts, means for normally forcing outwardly said bolts, means for locking the supporting means in normal position, separating means for said supporting means and said locking means, said separating means being provided with key guiding slots, the outer portion of said case being provided with a key entrance slot opposite said key guiding slots for a key to operate said bolt supporting means and said locking means, operating

members for said door engaging members, means for supporting said operating members in one position, and means carried by said case for locking the last-mentioned supporting means in operative position.

8. The combination with door engaging members; of a case, a guide member for said case, a cover for said guide member and case, a spring for resiliently retaining said case

- 10 in its uppermost position, bolts projecting from said case and adapted to extend into the sides of said guide member to lock said case in its lowermost position, pivoted members for supporting said bolts, means for locking said pivoted members in normal position, means coöperative with said pivoted members for forcing said bolts outwardly, operating levers for said door engaging members, connections between said operating levers and said door-engaging members, means coöperative with said cover for securing said levers in the proper position to retain said door-engaging members in operative position, and means carried by said case
- 15 to retain said cover in operative position.

9. The combination with a horizontally movable lower door section provided with a keeper, and a horizontally movable upper door section on said lower door section and provided with a keeper, of a vertically disposed channel bar mounted adjacent to one edge of the respective door sections, means on said channel bar movable into engagement with the keeper of the lower door section, means on said channel bar movable into engagement with the keeper of said upper door section, a pair of levers mounted within the channel of said channel bar and movable in a vertical plane, a link operatively connecting the first said means with one of said levers for effecting engagement of said means with the keeper of the lower door section, a link operatively connecting the other of said levers with the second said

- 45 means for effecting engagement thereof with the keeper of the upper door section, and universal means for locking said levers in their locking position.

10. The combination with a wall having a

door-way therein, and a pair of horizontally movable door sections for closing said door-way, of a vertically disposed channel bar having its intermediate portion spaced apart from said wall sufficiently to allow passage of said door sections between said wall and channel bar, a keeper carried by the lower door section, a keeper carried by the upper door section, means on said channel bar for engaging the keeper of the lower door section, means on said channel bar for engaging the keeper of the upper door section, a pair of levers pivotally mounted within the channel of said channel bar and movable about an axial line which is common to both of said levers, connecting means extending downward into coöperative relation with the said first means for effecting the locking of said lower door sections, connecting means extending upward from the other of said levers into coöperative relation with the second said means for effecting the locking of said upper door section, and means common to both of said levers for securing them in locking position.

11. The combination with a pair of door sections each provided with a keeper, of a channel bar secured adjacent to an edge of each of said door sections, means on said channel bar for engaging the keeper of one of said door sections, means on said channel bar for engaging the keeper of the other of said door sections, a pair of levers mounted within the channel of said channel bar and between the first and second said means, means common to both of said levers for detaining them in locking position and operable to simultaneously release both of the said levers and allow either of them to be moved for unlocking the door section correlated therewith, while the other lever of said pair may remain in its locking position.

In testimony whereof I affix my signature in presence of two witnesses.

WILLIAM LAYMAN.
